UNITED STATES PATENT OFFICE

120,335

DESIGN FOR A SAFE OR SIMILAR ARTICLE

Palmer Bescherer, York, Pa., assignor to York
Safe and Lock Company, York, Pa., a corporation of Delaware

Application December 23, 1939, Serial No. 89,105

Term of patent 14 years

To all whom it may concern:

Be it known that I, Palmer Bescherer, a citizen of the United States of America, residing at York, in the county of York and State of Pennsylvania, have invented a new, original, and ornamental Design for a Safe or Similar Article, of which the following is a specification, reference being had to the accompanying drawings, forming part thereof, wherein

Figure 1 is a perspective view looking towards the front of the safe, showing my new design; and Fig. 2 is a perspective view looking towards the back of the safe.

I claim:

The ornamental design for a safe or similar article, as shown.

PALMER BESCHERER.
